UNITED STATES PATENT OFFICE

CHARLES WILLIAM HAMPTON, OF SHEFFIELD, ENGLAND

VISE

Application filed November 10, 1928, Serial No. 318,531, and in Great Britain November 14, 1927.

This invention relates to vises of the type known as woodworkers' vises in which the gripping faces are of plate-form to provide a grip of substantial area, and the movable jaw, 5 operated by a screw engaging a nut or half nut carried by the fixed jaw, is provided with two parallel cylindrical slides fitting guides in the fixed jaw, the object of the invention being to provide an improved and portable 10 construction of woodworker's vise which may also be combined with a cramp.

In the accompanying drawings:—

Figure 1 is an elevation of a vise adapted for use according to the present invention.

15 Figure 2 is an end view of Figure 1.

Figure 3 is a plan view of Figure 1.

Figure 4 is a plan of a combined vise and cramp according to the present invention.

Figure 5 is a sectional elevation on the line 20 5—5 of Figure 4.

Figure 6 is a part plan illustrating a modification and

Figure 7 is a section on the line 7—7 of Figure 6.

25 Like reference numerals indicate like parts throughout the drawings.

In the vise illustrated the movable jaw 11, which has a gripping face of plate-like form as illustrated, is operated in the usual manner 30 by means of a screw 12 turned by a handle 13 and engaging a nut or half nut carried by the fixed jaw 14. This jaw 14 has a plate-like gripping face similar to that of the movable jaw 11. The jaw 11 is provided with two parallel cylindrical slides 15 fitting guides in the

35 fixed jaw 14. According to the present invention the fixed jaw 14 is formed with a clamping base 16 at right angles to its gripping face and with a suitably shaped bracket 17 extending from its lower edge. The bracket 17 carries a clamping screw 18 movable towards and away from the clamping base 16 and operated by a suitable handle 19.

40 In this manner a portable woodworker's vise is provided which may be clamped, as shown 45

in Figure 1, to the edge of a bench or table at any desired portion thereof, the screw 12 and slides 15 passing over the surface of the bench.

If desired the clamping base 16 and bracket 50 17 may be bored as indicated at 20 to receive fixing screws when it is desired more permanently to fit the vise.

The vise may be combined with a cramp as shown in Figures 4 and 5 by providing a 55 cramping bar 21 extending from the rear of the fixed jaw 14 and by fitting cramping shoes 22 and 23 to the bar 21 and to the movable slides 15 of the vise respectively.

In the construction illustrated the vise 60 clamping base 16 is formed with a recess 24 having a restricted opening leading to the rear edge of the base, while the cramping bar 21 is provided with a head 25 engaging the recess 24 and with a neck-like portion 26 passing through the restricted opening. The head 25 of the cramping bar 21 is thus unable 65 to pass through the restricted opening and so the bar is anchored to the fixed jaw of the vise.

70 Preferably the recess 24 and head 25 are circular in outline as illustrated, and the neck 26 is narrower than the opening of the recess so that the cramping bar 21 may either extend at right angles to the gripping faces of the vise jaws or may be turned to lie at an angle thereto as indicated by dotted lines in Figure 4.

The cramping shoe 22 is adjustable and 75 may be fitted at the desired position along the bar 21 by means of a clamping screw 27 passing through the shoe as shown in Figure 5 and engaging the desired one of a series of tapped holes 28 in the bar 21. If desired the shoe 22 may also be provided with a projecting stud 29 which may be carried by a screw 30 adapted to engage one of a series of plain holes 31 in the bar 21. The holes 31 are disposed to position the gripping surface of the cramping shoe 22 at right angles to the length 80 85 90 95

of the bar 21, but if desired the pin 29 may be omitted or rendered inoperative by means of the screw 30 carrying it so that the shoe 22 may also be adjusted on the bar 21 about the 5 pivot formed by the screw 27, or by a pin replacing that screw. If desired the shoe 22 may be locked in the adjusted position about such pivot by engagement of the stud 29 with other suitably disposed holes in the bar 21.

10 The other cramping shoe 23 is fitted to the slides 15 of the vise for which purpose it is formed with sockets or hollow bosses 32 fitting these slides. One or more set screws may be fitted to the hollow bosses 32 in order more firmly to secure the shoe 23 to the slides 15.

15 Thus the cramping bar 21 may be disposed at right angles to the faces of the vise jaws 11 and 14 with the gripping surfaces of the cramping shoes 22 and 23 parallel to the vise 20 jaw faces as shown in full lines in Figure 4.

20 If desired, however, the cramping bar 21 may be turned to an angle with the vise jaw faces while the cramping shoe 22 may be adjusted both as to position along the bar 21 and also 25 about the axis of the screw or pin 27 for different purposes, various positions of the cramping bar 21 and shoe 22 being indicated by dotted lines in Figure 4.

For cramping a rectangular frame the 30 shoes 22 and 23 may be formed to engage the interior and exterior angles of the frame. In the modification illustrated in Figures 6 and 7 the movable shoe 23' (provided with the socket 32' to fix the slide 15) is formed 35 with a ledge 33 to support the frame and with abutments 34 to engage its exterior edge. The abutments 34 are grouped along the desired angle or may be replaced by flanges extending from the ledge 33.

40 The relatively fixed shoe 22' is provided with abutments 35 to engage the interior angle of the frame which is indicated in chain lines in Figure 6 thus clamped between the two shoes, the abutments 35 being preferably situated above a supporting surface 36 45 of the shoe 22' corresponding in height to the ledge 33 and assisting that ledge in supporting the frame above the cramping bar 21.

If desired similar ledges may be provided 50 in the shoes illustrated in Figure 4 to support the work being cramped.

What I claim is:—

1. In a woodworker's vise the combination of a fixed jaw having a plate-like gripping 55 face and formed with a clamping base at right angles to its gripping face and with a circular recess in the clamping base having a restricted opening leading to the rear edge thereof, the fixed jaw being also formed with a bracket extending from the lower edge of 60 its gripping face, a clamping screw carried by the bracket, a movable jaw operated by a screw engaging a nut carried by the fixed jaw, two parallel cylindrical slides on the 65 movable jaw fitting guides in the fixed jaw

and passing above the clamping base, a cramping bar provided with a head fitting the recess in the clamping base and with a neck-like portion narrower than and passing through the restricted opening of the recess, a cramping shoe adjustably fitted to the bar and a co-operating cramping shoe formed with sockets fitting the ends of the vise slides, substantially as specified. 70

2. In a woodworker's vise the combination 75 of a fixed jaw having a plate-like gripping face and formed with a clamping base at right angles to its gripping face and with a circular recess in the clamping base having a restricted opening leading to the rear edge thereof, the fixed jaw being also formed with a bracket extending from the lower edge of its gripping face, a clamping screw carried by the bracket, a movable jaw operated by a screw engaging a nut carried by the fixed jaw, 80 two parallel cylindrical slides on the movable jaw fitting guides in the fixed jaw, and passing above the clamping base, a cramping bar provided with a head fitting the recess in the clamping base and with a neck-like portion narrower than and passing through the restricted opening of the recess, a cramping shoe adjustably fitted to the bar and provided with abutments to engage the interior 85 edge of a rectangular frame and a co-operating cramping shoe formed with sockets fitting the ends of the vise slides, and formed with a ledge to support the frame and with abutments to engage its exterior edge, substantially as specified. 90

3. In a woodworker's vise, the combination 95 with a fixed jaw having guides and a movable jaw, of a slide on said movable jaw co-operating with said guides, means for securing the fixed jaw to a bench with the movable jaw 100 slide passing through the fixed jaw above the bench surface, a cramping bar extending from the rear of the fixed jaw and adjustable to different angular positions with respect thereto, a cramping shoe adjustably fitted to the bar and a co-operating cramping shoe fitted to the slide of the movable jaw, 105 substantially as specified.

4. In a woodworker's vise, the combination 110 of a fixed jaw provided with guides and having a clamping base at right angles to its gripping face with a recess formed in the clamping base having a restricted opening leading to the rear edge of the base, a movable jaw, a slide on said movable jaw co-operating with said guides, a cramping bar provided with a head engaging the recess and with a neck-like portion passing through the restricted opening, and co-operating cramping shoes fitted to the bar and to the movable 115 jaw slide respectively, substantially as specified. 120

5. In a woodworker's vise, the combination 125 of a fixed jaw provided with guides and having a clamping base at right angles to its 130

gripping face with a circular recess formed in the clamping base having a restricted opening leading to the rear edge of the base, a movable jaw, a slide on said movable jaw co-operating with said guides, a cramping bar 5 provided with a head fitting the recess and with a neck-like portion, narrower than and passing through the restricted opening, and co-operating cramping shoes fitted to the bar and to the movable jaw slide respectively, 10 substantially as specified.

In testimony whereof I hereunto affix my signature.

CHARLES WILLIAM HAMPTON.
